(57) CLAIM

The ornamental design for a tub for bathing, as shown and described.

DESCRIPTION

FIG. 1 is a left, top, front perspective view of a tub for bathing embodying our new design;
FIG. 2 is a top plan view thereof;
FIG. 3 is a front elevational view thereof, the rear elevational view being a mirror image of the front elevational view shown;
FIG. 4 is a right side elevational view thereof; and,
FIG. 5 is a left side elevational view thereof.
The broken line representation of a hole in FIGS. 1 and 4 is for the purpose of illustration only, and forms no part of the claimed design.
